UNITED STATES PATENT OFFICE

GILBERT S. ELLITHORPE, OF CHICAGO, ILLINOIS.

SHOE-HEEL.

1,272,929.

Specification of Letters Patent. Patented July 16, 1918.

Application filed July 26, 1917. Serial No. 182,868.

To all whom it may concern:

Be it known that I, GILBERT S. ELLITHORPE, a citizen of the United States, residing at Chicago, in the county of Cook and State of Illinois, have invented certain new and useful Improvements in Shoe-Heels, of which the following is a specification.

My invention relates to improvements in shoe heels and has especial reference to heel lifts and inherent means for securing them to the shoe.

One of the objects of my invention is to provide a shoe lift, preferably composed of a resilient, moldable material, such as rubber or the like, and attaching means resilient therein, whereby the lift may be secured to the heel of the shoe by unskilled persons and without the use of separate brads, screws or other attaching instrumentalities.

Another object of my invention is to provide a shoe heel or lift having a flat area, or zone within the region of which the attaching means is located and a surrounding marginal edge or portion laterally deflected at a suitable angle to provide a pseudo concavo-convex inner and outer surface whereby to exert a resilient stress upon the edge of the lift to hold it in intimate contact with the contacting edge of the shoe structure, while the center zone is at all times flat.

Other and further objects of my invention will become readily apparent to persons skilled in the art, from a consideration of the following description when taken in conjunction with the drawings, wherein:

Figure 1 is a central section of the lift taken on line 1—1 of Fig. 3.

Fig. 2 shows a similar section of the lift after it has been applied to a shoe.

Fig. 3 is a plan view of the underneath or tread side of the lift, showing parts broken away to expose the upper surface of the attaching device.

Fig. 4 is a cross section of one form of attaching device; and

Fig. 5 is a similar view of a modified form of attaching device.

Fig. 6 is a view of the convex side of the lift with the position of the fastener shown by dotted lines.

In all the views the same reference characters are employed to indicate similar parts.

The heel or lift 5, is made of moldable

and, preferably, resilient material, such as rubber or the like, and is provided with a flat central outer surface 6 and a parallel flat central inner surface 7 with downwardly or laterally deflected surrounding edges 8 and 9, thereby to provide a partially concave surface 10 and a partially convex surface 11, and when the lift is in place on the shoe, the surface 8 is substantially parallel with the surface 6, as shown in Fig. 2. The attaching device 15 is provided with a flat upper or head portion 16, which lies between the flat surfaces 6 and 7 of the lift. In the particular showing the device 15 is provided with three downwardly projecting prongs or brads 17, which taper gradually, preferably, to a relatively sharp point 18, from each of its sides, the brads being held together by a rim 19, which is an integral part of the structure. The brads have chisel points, being preferably sharpened from the inside surface, as at 20, so that when the brads are driven into the lift of the shoe, they will be deflected laterally, as shown in Fig. 2. The outward turning of the brads is produced by the peculiar manner in which they are sharpened. The chisel edge is in the same vertical plane as one edge of the brad, and therefore when the device is driven, by the application of a hammer to the flat surface 6, the brads will take a lateral course from the perpendicular, as soon as they enter the lower leather lift 14 of the shoe heel, and continue in such path as shown in Fig. 2, until the heel lift 5 is in proper position on the leather lift of the shoe, thereby rendering the device difficult of removal, without breaking the attaching means. I may place the outward projections 22 and inward projections 23 upon the device 15 to prevent it from turning in the lift 5 and to give the attaching brads 17 more superficial contact with the material in which they are embedded.

I have shown a modification 15' in Fig. 5 of the device shown in Fig. 4, in which the brads 17' are serrated on their edges, as at 25, so as to make them cling more tenaciously to the substance through which they may be driven in applying the lift to the shoe.

One of the important features of my invention is the permanent association of the attaching device with the lift, and another important feature of the invention is the joining together of the brads or attaching

means 17 at or near their upper ends, so that they will not be initially inclined out of a true perpendicular at the time when they are being driven into the substance of 5 the shoe heel, in the act of attaching the lift to the heel.

While I have herein shown but two embodiments of my invention for the purpose of clear disclosure it is manifest that changes 10 may be made in the general arrangement and configuration of the parts within the scope of the appended claims.

Having described my invention, what I claim is:—

- 15 1. A tread lift of resilient material having a tread face provided with a relatively flat central portion and deflected marginal portions, and a body portion concavo-convex in transverse section, the forward edge or breast portion of the lift having curved upper and lower edges, and fastening means embedded in the body of the lift within the central portion located and arranged to exert a substantially equal pressure coextensive with 20 said central portion.
- 20 2. A tread lift of resilient material having a tread face provided with a relatively flat central portion and deflected marginal portions, and a body portion concavo-convex 25 both in longitudinal and transverse section and bounded by curved upper and lower edges, and fastening means embedded in the body of the lift within the central portion located and arranged to exert a substantially equal pressure coextensive with said central

portion and partly projecting therefrom to secure the lift to the shoe.

3. A heel lift comprising a body of resilient material of concavo-convex form and having a substantially flat central tread surface area and laterally deflected margins of substantially uniform thickness bounded by curved upper and lower edges, and attaching means embedded within said flat central portion located and arranged to exert a substantially equal pressure coextensive with said central portion.

4. A cushion heel lift, comprising a resilient body, the upper and lower faces of which are mainly concave and convex respectively, 40 the central portion of said body being of substantially circular flattened form, and fastening means embedded in the body of the lift within the central portion located and arranged to exert a substantially equal pressure coextensive with said central portion.

5. A resilient heel lift of concavo-convex shape and being centrally flat, the upper and lower surfaces of which coincide with the 45 respective surfaces of revolution of a pair of lines intersecting the vertical axis of said lift, one above the other, said lines being straight and perpendicular to said axis adjacent to the latter to a certain point, and diverging therefrom downwardly and outwardly to the edge of the lift.

In testimony whereof I hereunto set my hand.

GILBERT S. ELLITHORPE.
